ATTORNEYS

UNITED STATES PATENT OFFICE.

OTTO EICK, OF ST. LOUIS, MISSOURI.

BOTTLE STOPPER.

Application filed August 27, 1925. Serial No. 52,908.

To all whom it may concern:

Be it known that I, Otto Eick, a citizen of the United States, and resident of St. Louis, in the State of Missouri, have invented certain new and useful Improvements in Bottle Stoppers, of which the following is a specification.

My invention relates to improvements in bottle stoppers, and it consists in the combinations, constructions and arrangements herein described and claimed.

An object of the invention is the provision of a stopper which without the use of any tools can be quickly and easily applied to or removed from any bottle of the type that is adapted to have a crown or cap applied thereto, and which is adapted when in applied position on a bottle neck to seal the mouth of the bottle effectively and securely.

A further object of the invention is the provision of a quickly detachable and attachable bottle stopper having a novel and easily applied fastening device for engaging with the bottle neck to hold the body or sealing member of the stopper in position to seal the bottle mouth.

A still further object of the invention is the provision in a stopper of the character described of a novel sealing member which is adapted to fit in the mouth of the bottle to seal the latter at the inner side thereof and to be expanded at its inner end against the inner wall of the bottle neck by pressure from within the bottle.

A still further object of the invention is the provision of a bottle stopper of the character described which is thoroughly sanitary, reliable in use, and practical commercially.

Other objects and advantages of the invention will be apparent from the following description, considered in conjunction with the accompanying drawings, in which:

Figure 1 is a perspective view of the improved stopper applied to a bottle;

Figure 2 is a longitudinal vertical section through the sealing member of the stopper, showing the fastening member of the stopper in elevation;

Figure 3 is a perspective view of the stopper detached from the bottle neck and

raised from position to close the mouth of the bottle, and

Figure 4 is a plan view of the length of wire of which the fastening member of the stopper is formed.

The improved stopper is adapted for use with a bottle of the type having a neck portion provided with a mouth adapted to be closed by a cap or crown. A bottle of the type just referred to is partially shown in Figs. 1 to 3 inclusive, of the drawings and includes a neck portion 1 formed with an external bead 2 at the mouth thereof and with an external annular shoulder 3 which faces in a generally downward direction and is located at a lower level than the bead 2.

The body of the improved stopper comprises a sealing member or closure 4 made of rubber or like compressible resilient material and adapted to be forced into the mouth of the bottle neck until a flange 5 at the outer end of the sealing member bears against the outer end of the bottle neck.

The sealing member 4 is formed with an annular marginal sealing extension 6 at its inner end, the inner wall of which is beveled or inclined inwardly as shown, so that the inner diameter of the sealing extension 6 decreases from the outer end to the inner end of said sealing extension.

The sealing member 4 has a central cavity 7 extending from the outer face of the sealing member for part of the length of the latter and enlarged at its inner end as indicated at 8 to receive the enlarged inner end portion 9 of the stem 10 of an attaching head 11 which is made of metal and is disposed flatwise against the outer face of the sealing member 4. The attaching head 11 has an integral eye portion 12 extending from the outer face of the attaching head centrally of the latter.

The fastening means that the invention provides for securing the body of the stopper in position to close the mouth of the bottle is formed of a single length of spring wire such as is shown in Fig. 4. This length of spring wire is bent intermediate the ends thereof to produce a substantially U-shaped bottle neck engaging or clamping member having a web portion 13 and a pair

of arms 14. The end portions of the length of spring wire are bent rearwardly at their junctures with the arms 14 and extend for a slight distance along the arms 14, thus defining the spring return bend or half loop portions 15. The end portions of the length of spring wire then are bent upwardly at 16 from their junctures with the outer arms of the spring return bend portions 15. One end portion of the length of spring wire then is bent laterally inward across the attaching head 11 and through the eye 12, as indicated at 17, across the outer end of the body of the stopper and finally downward and inward at 18 to position to engage at its extremity with the lower face of the bead 2 on the bottle neck. The other end portion of the length of spring wire is bent from its juncture with the second upwardly extending portion 16 of the fastening device across the outer face of the stopper body, as indicated at 19, being arched at 20 at the center of the outer face of the stopper to clear the eye 12 on the attaching head 11. The extremity of the last named end portion of the length of spring wire then is bent inwardly and downwardly at 21 to engage with the lower face of the bead 2 on the bottle neck at a point on the latter approximately diametrically opposite to the point of engagement of the end portion 18 of the stopper fastening means with the lower face of the bead 2. The end portions 18 and 21 therefore may be termed cooperative spring clamping fingers.

The web 13 of the substantially U-shaped neck embracing portion of the stopper fastening means is bent slightly inward intermediate its length as indicated at 22 to provide an additional contact portion for engaging with the bottle neck and to assure a relatively great resistance to any force which tends to spread the arms 14 apart from position to straddle and closely contact the bottle neck at the juncture of the shoulder 3 with the lower portion of the bottle neck.

From the foregoing description of the various parts of the device, the operation thereof may be readily understood. In applying the stopper to the bottle, the sealing member 4 is forced by manual pressure into the mouth of the bottle neck and the spring fingers 18 and 21 are swung to positions to engage with the lower face of the bead 2. Pressure then is exerted on the web 13 of the substantially U-shaped bottle neck engaging portion of the fastening means until the arms of said substantially U-shaped portion of the fastening means swing inwardly and downwardly in straddling relation to the bottle neck and against the shoulder 3, thus causing a pull to be transmitted through the spring return bend portions 15 and the upwardly extending portions 16 to the upper

clamping members 17 and 19. The contact of the spring fingers 18 and 21 with the bead 2 thus will be tightened and the body of the stopper will be pressed to position to seal the mouth of the bottle. When the web 13 of the substantially U-shaped portion of the stopper fastening means is in contact with the bottle neck, the arms of said substantially U-shaped neck embracing portion will be held clamped against the bottle neck also at points slightly beyond the center line of the bottle neck as a result of the spring action of the spring return bend portions 15. The stopper therefore will be securely attached to the bottle neck and held against accidental displacement although it can be instantly detached from the bottle neck as a result of manual action when desired.

The effect of pressure from within the bottle on the sealing member of the improved stopper will be to expand the annular extension 6 against the inner wall of the bottle neck, thus tending to make the sealing action of the stopper more positive than when pressure does not exist in the bottle.

Obviously, the invention is susceptible of embodiment in forms other than that which is illustrated in the accompanying drawings, and I therefore consider as my own all such modifications and adaptations thereof as fairly fall within the scope of the appended claims.

I claim:

1. In a stopper, a sealing member adapted to enter the mouth of a bottle, an attaching head superimposed on the sealing member and having a stem secured in a cavity in the outer end portion of said sealing member, said attaching head having an outwardly extending eye, and a one piece fastening member having a substantially U-shaped portion for embracing the neck of the bottle against a shoulder on the latter, spring portions for clamping the arms of said substantially U-shaped portion to said bottle neck, end portions engaging the attaching head and adapted to press the sealing member into the mouth of the bottle, said end portions extending transversely across said attaching head and having their extremities adapted to engage with a bead at the outer end of the bottle neck, and other portions connecting said sealing member pressing portions with said arm actuating spring portions of the fastening member.

2. In a stopper, a sealing member adapted to enter the mouth of a bottle, an attaching head superimposed on the sealing member and having a stem secured in a cavity in the outer end portion of said sealing member, said attaching head having an outwardly extending eye, and a one piece fastening member having a substantially U-shaped portion for embracing the neck of the bottle

against a shoulder on the latter, spring portions for clamping the arms of said substantially U-shaped portion to said bottle neck, end portions engaging the attaching head and adapted to press the sealing member into the mouth of the bottle, said end portions extending transversely across said attaching head and having their extremities adapted to engage with a bead at the outer end of the

bottle neck, and other portions connecting 10 said sealing member pressing portions with said arm actuating spring portions of the fastening member, one of said sealing member pressing portions of the fastening member being threaded through said eye of the 15 attaching head.

OTTO EICK.
